Des. 214,410
Patented June 10, 1969

214,410

TIRE

Horace Victor Barlow, deceased, late of Roma, Hampton on the Hill, near Warwick, England, by Beatrice Lilian Barlow, administratrix, Roma, Hampton on the Hill, near Warwick, England, assignor to The Dunlop Company Limited, Birmingham, England, a corporation of Great Britain

Continuation of design applications Ser. No. 8,021 and Ser. No. 8,023, July 27, 1967. This application Jan. 24, 1968, Ser. No. 10,781

Claims priority, application Great Britain Apr. 11, 1967

Term of patent 14 years

Int. Cl. D12—14

U.S. Cl. D90—20

FIG. 2

FIG. 3

FIG. 5

FIG. 6

FIG. 1 is a perspective view of a tire showing the new design in only a portion of the circumference of the tire between the lines X-Y, it being understood that the design is repeated throughout the circumference of the tread of said tire;

FIG. 2 is a fragmentary perspective view of the tire in section showing the design;

FIG. 3 is a fragmentary plan view of the design of the tire shown in FIG. 1;

FIG. 4 is another embodiment of the design showing in a perspective view only a portion of the circumference of the tire between the lines X-Y, it being understood that the design is repeated throughout the circumference of the tread of said tire;

FIG. 5 is a fragmentary perspective view of the tire shown in FIG. 4 in section; and

FIG. 6 is a fragmentary plan view of the design shown in FIG. 4.

This is a continuation of applications Ser. Nos. D. 8,021 and D. 8,023, both filed respectively on July 27, 1967, and now abandoned.

What is claimed is:

The ornamental design for a tire, substantially as shown and described.
